FURNACE

Martin Frisch, New York, N. Y., assignor to Foster Wheeler Corporation, New York, N. Y., a corporation of New York

Continuation of application Serial No. 343,965, July 5, 1940. This application October 21, 1942, Serial No. 462,854

5 Claims. (Cl. 122—235)

This invention relates to furnaces and more particularly pertains to furnaces adapted for continuous slagging operation.

In the operation of such furnaces in steam generating apparatus, molten slag which is deposited on the furnace floor, flows continuously therefrom through a slag discharge opening which may be in the form of a throated slot extending across the width of the furnace floor and midway between the front and rear walls of the furnace, or the discharge opening may be adjacent and parallel to the rear furnace wall. The refractory lining of the furnace floor and the "throat" of the discharge opening are protected from excessive temperatures and the damaging effect of the molten slag, by water tubes which ordinarily are closely spaced and are connected into the boiler circulation. In order to protect the portions of these tubes which are directly exposed to the molten slag, a coating or "blanket" for the tubes of some highly heat resistant refractory material, such as chrome plastic, may be employed. However, unless some satisfactory means is provided for retaining this refractory plastic coating in place on the exposed surfaces of tubes and floor, there is a tendency for it to be floated and washed away by the molten slag.

The present invention provides means for retaining a covering over the tubes of a furnace floor to protect the tubes from the effects of slag in furnaces of the slagging type.

The features and advantages which characterize the invention will be apparent from the following description when considered in connection with the accompanying drawing forming a part thereof and in which:

Fig. 1 is a partial vertical sectional view of a continuous slagging type furnace embodying the invention;

Fig. 2 is a sectional view taken on the line 2—2 of Fig. 4;

Fig. 3 is a partial plan view of the invention, and

Fig. 4 is a somewhat enlarged, partial sectional view, taken on line 4—4 of Fig. 1.

Referring to the drawing, reference character 10 designates generally a furnace of a steam generator having one or more burners for burning a slag forming fuel. The furnace, as shown, has substantially horizontal refractory floor portions 11 and 12, a front wall 13 and a side wall 14. A slag discharge opening or slot 15 extends across the width of the furnace floor at right angles to the side walls and midway between the front

and rear furnace walls. The refractory floor portions are lined with closely spaced parallel water tubes 16 and 17, which as shown, form part of the circulatory system of the steam generating unit. Below the slot 15 and in open communication therewith, is a water-sealed reservoir, not shown. Directly beneath the straight horizontal portions of the tubes 16 and 17 is one or more layers of interlocking, wedge-shaped tiles 18 and 19 respectively. The individual tiles are free to move relatively to each other in such a way that any expansion of the floor is absorbed by a minute vertical displacement of the interlocking tiles without providing spaces for slag seepage through the floor. Such a floor structure takes care of localized expansions, or the expansion of individual sections of a floor, rather than conveying such expansion to the entire floor structure cumulatively, and also provides a structure in which relative movement of the floor units will be such as to maintain an essentially slag tight contact between the units. The tiles may be constructed and arranged as disclosed in Frisch and Wooley Patent No. 1,896,669, granted February 7, 1933. Welded to the upper portion of the external peripheries of the horizontal portion of the floor tubes 16 and 17 at widely spaced intervals are a plurality of metallic lugs 20. These lugs are disposed in spaced planes which extend transversely of the tubes and are arranged so that adjacent lugs on adjacent tubes are in alignment, thus providing a plurality of dams spaced apart a substantial distance and which extend transversely of the tubes for the full width of the furnace and parallel to the slag discharge opening. Lugs 21, which are similar to lugs 20, are positioned on the curved portion of the tubes 16 and 17 and are disposed in spaced planes that extend transversely of the tubes. The arrangement is such that adjacent lugs on adjacent tubes are in alignment, thus providing a plurality of spaced dams on the curved portion of the tubes. As shown, these dams are more widely spaced on the straight horizontal floor portions of the tubes 16 and 17, than they are on the curved portions of the tubes which extend into the throat of the slag discharge opening. Chrome ore or an equivalent heat resisting plastic material is inserted in the spaces between floor tubes and is built up on the tube surfaces in the spaces between adjacent dams as shown in the drawing. A highly heat-resisting protective "blanket" or coating is thus provided for the tubes and for any portions of the refractory

furnace floor that would be exposed otherwise to direct contact with the molten slag.

In operation, a slag, indicated in Fig. 2 by the reference numeral 22, forms in the furnace and flows along the floor towards the throat of the discharge opening 15, the protecting blanket 23 of chrome plastic is held in place by the dams on the tubes. If, due to the constant drag of the moving molten slag, some of the top coating of the chrome ore is washed away, as shown in Fig. 2, it will be replaced by a layer of slag which freezes in the region adjacent the water-cooled surface of the tubes, although the slag is molten thereabove. Such a layer of frozen slag is self-replacing and insulates the tubes from the flowing molten slag. Thus the dams serve not only to retain the chrome ore in place, but also act to retard the flow of molten slag to a sufficient extent to provide a "frozen" layer of slag adjacent the tube surfaces which affords a permanent protection for the furnace floor.

The molten slag flows into the discharge opening in a number of streams and into the water-sealed reservoir without touching the exposed sections 16' and 17' of the water tubes which form the lower portion of the throat of the discharge and are bent away from the throat so as to promote the disengagement of the slag from the tube surface. As the radiant heat of the slag streams is absorbed by these tube sections, the slag is chilled and becomes less viscous, stretching into threads which freeze as they drop into the water in the reservoir and break up into needles which are sluiced out at suitable intervals.

It will be apparent that the invention is not limited in its application to furnaces of steam generating apparatus, but that it is capable of general application to furnaces of the slagging type.

This application is a continuation of an application bearing Serial Number 343,965 filed July 5, 1940.

Although a preferred embodiment of the invention is disclosed herein, it is to be understood that changes may be made in the form, location and relative arrangement of the several parts of the apparatus without departing from the principles of the invention, which is not to be limited excepting by the scope of the appended claims.

What is claimed is:

1. A furnace floor having a slag discharge opening therein, said floor comprising a plurality of blocks in relatively sliding contact with respect to each other, each of said blocks having a side in contact with an oblique side of an adjacent block, fluid conducting tubular members lining said blocks on the furnace side thereof and extending downwardly through said opening, and lugs secured to the tubular members and spaced axially a substantially greater distance from one another on portions of the tubes other than the downwardly extending portion than on the downwardly extending portion, said lugs being so disposed as to provide a plurality of dams extending substantially transversely of the tubes for retaining a covering of refractory material on said members.

2. A furnace floor having a slag discharge opening therein, said floor comprising a plurality of blocks in relatively sliding contact with respect to each other, each of said blocks having an oblique side in contact with an oblique side of an adjacent block, fluid conducting tubular members lining said blocks on the furnace side there-

of and extending downwardly through said opening, and lugs secured to the tubular members and spaced axially a substantially greater distance from one another on portions of the tubes other than the downwardly extending portion than on the downwardly extending portion, said lugs being so disposed as to provide a plurality of dams extending substantially transversely of the tubes for retaining a covering of refractory material on said members.

3. A substantially horizontal furnace floor having a slag discharge opening therein, said floor comprising a plurality of blocks in relatively sliding contact with respect to each other, each of said blocks having a side in contact with an oblique side of an adjacent block, a plurality of laterally spaced, substantially horizontally extending tubular members disposed on the furnace side of said blocks which members are curved adjacent the slag discharge opening to extend downwardly therethrough, means forming a plurality of dams, said dams comprising a plurality of lugs secured to the members in axially spaced planes and embracing at least a part of the circumference thereof, the lugs on the curved portion of the tubular members being spaced apart axially a predetermined distance and the lugs on the horizontal portion of the members being spaced apart axially a distance several times greater than the distance between the lugs on the curved portion, said lugs extending transversely of the members, a portion thereof projecting beyond the members on the furnace side thereof and another portion projecting into the space between the members, the lugs being so arranged and disposed on the members that adjacent lugs on adjacent tubes are in lateral alignment, and a covering of heat resistant plastic material over the members and extending between said members and said dams, the construction and arrangement being such that the dams will retain the covering of heat resistant material on the horizontal portion of the members and in the event part of said material is eroded by the flowing of slag thereover will retard the flow of molten slag sufficiently to form a protective coating over the eroded portion of the covering and prevent further erosion thereof.

4. A substantially horizontal furnace floor having a substantially centrally disposed slag discharge opening, said floor comprising a plurality of blocks in relatively sliding contact with respect to each other, each of said blocks having a side in contact with an oblique side of an adjacent block, a plurality of laterally spaced, substantially horizontally extending tubular members disposed on the furnace side of said blocks which members are curved adjacent the slag discharge opening to extend downwardly therethrough, means forming a plurality of dams, said dams comprising a plurality of lugs secured to the members in axially spaced planes and embracing at least a part of the circumference thereof, the lugs on the curved portion of the tubular members being spaced a predetermined distance axially and the lugs on the horizontal portion of the members being spaced apart axially a distance several times greater than the distance between the lugs on the curved portion, said lugs extending transversely of the members, a portion thereof projecting beyond the members on the furnace side thereof and another portion projecting into the space between the members, the lugs being so arranged and disposed on the members that adjacent lugs on adjacent tubes are in lateral alignment.

alignment, and a covering of heat resistant plastic material over the members and extending between said members and said dams, the construction and arrangement being such that the dams will retain the covering of heat resistant material on the horizontal portion of the members and in the event part of said material is eroded by the flowing of slag thereover will retard the flow of molten slag sufficiently to form a protective coating over the eroded portion of the covering and prevent further erosion thereof.

5. A furnace floor having a slag discharge opening therein, said floor comprising a plurality of

blocks in relatively sliding contact with respect to each other, each of said blocks having an oblique side in contact with an oblique side of an adjacent block, fluid conducting tubular members lining said blocks on the furnace side thereof and extending downwardly through said opening, and lugs secured to the tubular members and spaced axially thereon, said lugs being so disposed as to provide a plurality of dams extending substantially transversely of the tubes for retaining a covering of refractory material on said members.
